UNITED STATES PATENT OFFICE.

FRANK M. ZOTTOLI, OF BOSTON, MASSACHUSETTS.

TURBINE WHEEL.

Application filed June 6, 1922. Serial No. 566,396.

To all whom it may concern:

Be it known that I, FRANK M. ZOTTOLI, a citizen of the United States, residing at Boston, county of Suffolk, State of Massachusetts, have invented a certain new and useful Improvement in Turbine Wheels, of which the following is a specification, reference being had therein to the accompanying drawings.

10 The invention relates to a new and useful improvement in turbine wheels and systems, and is an improvement on the invention shown and described in an application filed by me December 3, 1921, Serial No. 519,753.

15 One feature of the invention relates to the construction of the turbine wheel itself and its mount, and consists in so constructing the wheel and the float on which it is mounted that it will rise and fall as the 20 water rises and falls.

Another feature of the invention relates to the construction of the channel or canal in which the turbine wheel is set so that the wheel will be driven in whichever direction 25 the current flows, and to accelerate and increase the force of the current.

Another feature of the invention consists in making the blades of the wheel hollow.

Another feature of the invention relates 30 to the means for storing up water in a reservoir during the rising of the tide to furnish a source from which the flow will be controlled to drive the wheel or wheels at the change of the tide either full tide or low 35 tide when the current is normally very slow or dead.

As is well known, the flow of the tide has the strongest current when it is midway between high and low and from that point 40 it diminishes as it approaches high tide or as it approaches low tide. One feature of the invention is to provide means whereby the rate of flow through the channel in which the turbine wheel is located will be 45 maintained practically uniform throughout the various stages of the ebb and flow of the tide.

Other features of the invention will be 50 more particularly set forth and described hereinafter.

The invention will be fully understood from the following description when taken in connection with the accompanying drawings, and the novel features thereof will 55 be pointed out and clearly defined in the claims at the close of this specification.

In the drawings, Fig. 1 is a diagram of a system for a single channel and reservoir embodying the invention.

Fig. 2 is a diagram showing a system with 60 a single channel and a double reservoir.

Fig. 3 is a diagram showing a system with a single reservoir and a double channel.

Fig. 4 is a horizontal sectional view showing a single turbine wheel in a channel 65 equipped with devices for controlling the current so as to insure a uniform speed of flow during the various changes in the tide.

Fig. 5 is a sectional view on line 5—5 of Fig. 4.

Fig. 6 is an end view of the apparatus shown in Fig. 4.

Fig. 7 is a plan view on an enlarged scale of one of the turbine wheels, showing the upper set of blades in staggered relation 75 to the next lower set of blades on the same hub.

Fig. 8 is a plan view of one of the current controlling turbines shown in Fig. 6.

Fig. 9 is a horizontal sectional view of 80 a modified arrangement showing a channel with two turbine wheels disposed in a row transversely of the channel and cooperating with each other.

Fig. 10 is a vertical sectional view of a 85 modified form of float and mount for a wheel.

Fig. 11 is an enlarged sectional view showing the construction of one of the hollow blades and its pivotal connection with 90 the hub of the wheel.

Referring now to the drawings, A represents one of the turbine wheels embodying the invention which will usually be arranged in a system, as shown in Figures 95 1, 2 and 3, containing a plurality of said wheels. The preferred form of such wheel, as shown in Figures 4, 5, 7 and 9, has a central hub 1, preferably made of some material which will float and is mounted on a 100 shaft 2 in such manner that the hub is capable of moving up and down on the shaft and will rotate with the shaft. In the form shown the shaft 2 is formed with longitudinal ribs 3 so that it is sort of star-shaped in cross section, that is, it is formed with a plurality of radiating projections 3 and the barrel 4 of the hub 1 is formed with a corresponding set of grooves with which said star ribs 3 engage, so that the shaft will 110 rotate with the hub and at the same time permit the hub to slide longitudinally there-

on. Any other suitable form of construction may be employed which will permit the hub to slide longitudinally on the shaft and to rotate with the shaft.

5 The hub of the wheel is normally seated upon a flange 5.

The shaft 2 is provided at its lower end with a head 7 which is journalled in a bearing in a member 9 and is seated upon washers 8. The member 9 is provided with an upwardly extending shell 11 formed with a flange 12 which engages over the upper side of the head 7 of the shaft to hold the said shaft from rising up out of its bearing.

15 On the upper end of the shaft 2 is mounted a gear wheel 13 adapted to engage with a gear, not shown, for transmitting movement to the mechanism which is to be driven.

20 The paddle blades 14 are pivotally connected with the hub 1 in series around its periphery, as shown in Figures 4 and 9. Preferably the blades instead of extending the full height of the hub are divided into 25 sections or into a series of sets one above another and with the blades of one section staggered with relation to those of the adjacent set above or below, as shown in Figures 5 and 7. In Figure 5 there are shown 30 three sets in vertical series. The object of arranging them in a vertical series and staggered is in order that more uniform action may be obtained. The sectional feature is shown in my prior application, No. 519, 35 753, previously mentioned but not in staggered relation.

Each blade 14 is pivotally connected with the hub at 15 as already described, and a stop member 16 is provided at the back side 40 of each blade to limit the backward movement of the blade.

45 Preferably each blade is made with a hollow interior 17, as shown in Figure 11, so that the blade may be light to aid in floating.

50 When the water rises above the level of the top of the upper blade of the wheel, as viewed in Figure 5, the wheel will rise on the shaft 2 by reason of the floating character of the hub 1 and thereby at all times receive the full force of the current, as the current is stronger at the top than at the bottom.

55 If the water falls below the upper series of blades when the wheel is at its lowest point, as shown in Figure 5, then the blades 14 of this series will be allowed to remain folded against the hub until they are brought into contact with the current again.

60 The hinged gate 18 is automatically operated by the current for two purposes,—one is to extend the amount of current which strikes against the blades of the wheel, and the other is to deflect the current so that it will be given direction toward the wheel to 65 open the blades and concentrate the current.

In the modified form of construction, shown in Figure 10, to allow for the vertical sliding movement of the wheel, the shaft 21 is made fast to the hub 22 of the wheel and the shaft 21 is vertically slidable in its bearing 23, so that the shaft rises and falls with the wheel. The hub of the wheel is mounted in a float 24 having a passage 25 therethrough to allow for the passage of water. Said float is formed with vertical guide holes 26 through which pass guide rods 27 to maintain the float in proper vertical alignment and prevent its rotation or drifting. The gear wheel 28 will rise and fall with the shaft.

70 The wheel, or wheels, if a system of wheels is employed, are intended to be set in a sluiceway having walls to direct the current or flow of water directly against the blades of the wheel. A simple form of such construction showing only a single wheel is illustrated in Figure 4. In this construction the sluiceway is provided with two vertical walls 30—30 and the wheel is set on end midway between the two walls. The wheel is adapted to be driven from right over to the left, as viewed in said figure and as will be plain from the disposition of the blades, as the current should strike against the concave face of the blade. As shown in said figure, the current for the time being is supposed to be flowing from the right toward the left. It is desirable that the current should be slightly deflected from a straight course through the sluiceway so as to strike as nearly as possible at right angles to the blades. The side walls 30—30 of the sluiceway are preferably of just sufficient distance apart from each other so that when the blades are extended to the full limit they 75 will just graze by the side of the wall, as shown at the upper part of Figure 4. In order to deflect the current in that direction, there is provided a vertical guide wall 31 extending toward the interior of the sluiceway on a curve from the wall 30 on the opposite side from that to which the current is intended to be deflected. On the diametrically opposite side of the wheel there is another curved guide 32 which is so set as to just allow the blades of the wheel to graze by on the latter part of their forward sweep so as to still keep the current substantially at right angles to the plane of the blades. This wall 32 is supplemented by a hinged 80 gate 18' to still continue the deflection of the current until it has passed the center and serving a similar purpose as the gate 18. On the latter half of the rotation of the wheel, that is, when the blades begin to travel again toward the right hand, the blades will be travelling against the resistance of the water and therefore they will be folded or partially folded against the side of the hub 85 of the wheel, as clearly shown in Figure 4,

until they swing around toward the front past the finger 18 once more ready to begin their forward movement again.

As already stated, the apparatus is intended to operate equally well whether the current is flowing in one direction or the other, and is, therefore, adapted to be used in tide water where the direction of current will flow for a period in one direction and then will reverse and flow in the other direction. In order, therefore, to deflect the current when it is reversed so as to flow from left to right, as viewed in Figure 4, there is provided a curved deflecting wall 31^a similar to the deflecting wall 31 but diametrically opposite therefrom, and there is also provided a deflecting wall 32^a directly opposite the deflecting wall 32.

It is well known that the current of tide water flows the slowest at the height of the flood and at the bottom of the ebb, and flows fastest at the intermediate stage, and it constantly decreases from said intermediate stage to the height of the flood or to the bottom of the ebb and conversely it increases from the two extremes to the middle.

One object of my invention is to provide means for controlling this normal variation, so that there will be a uniform rate of flow against the wheel at all stages. To this end I provide a sort of a gate at each end of the sluiceway in which are mounted a plurality of turbine wheels B placed parallel with each other and so constructed that they are somewhat elliptical in shape viewed in front elevation, as shown in Figure 6, that is, tapering from the middle toward the top and toward the bottom and placed as closely together as possible without interfering with each other. These wheels furnish a sort of check to the flow of the water, the greatest obstruction being at the middle of the wheels where they are widest and the obstruction diminishing toward each end. These are so set that the upper ends will be at about the level of the water when the water is at the highest and the lower ends will be at the level of the water when the water is at the lowest. It will thus be seen that the water will be the least obstructed where the spaces between the tapered portions of the wheels are the widest and the obstruction will be the greatest where the blades of adjacent wheels are nearest together and just clear each other. Thus the degree of check will vary with the variation in speed of the current due to changing level of the water and a practically uniform rate of flow will be maintained during all of the changes in tide level.

Preferably the wheels in these gateways are made in series one above another, as plainly shown in Figure 6. As shown in Figure 6 these wheels B are made in four vertical series. Those which are above the

water will for the time being be inoperative. The difference in the sweep of the wheels in the different series is obtained by varying the size of the hubs, the diameter to be varied according to the check required at the corresponding levels of flow.

It is not necessary that these check wheels shall extend to the bottom of the sluiceway. The shafts of these wheels are journaled in stationary bearings 33—34, at the top and bottom respectively.

I also provide means to prevent blocks of ice and other floating articles to be carried into the sluiceway. In order to prevent the large blocks of ice from being carried in, I provide rows of posts 35 at each end of the sluiceway a short distance from the entrance and spaced apart from each other at any desirable distance. Preferably there are two rows, one row outside of the other, and the posts in one row are arranged in staggered relation to the posts in the other row. Preferably also the posts in each row are in a line which makes an angle at the center, as clearly shown in Figure 4, the vertex of the angle pointing outwardly like the prow of a boat, so that the lines of the posts will serve to deflect the blocks of ice or other large floating articles, like timbers, and throw them off to one side as well as preventing their passage between the posts.

In order to still further form a guard against smaller floating objects, I provide a sort of stop or nose 36 composed of a board or boards which meet at an apex 37 in the middle and diverge backwardly, and this board extends across the entire end of the sluiceway from one side wall to the other. This board should not extend to the bottom but only a short distance down into the water, so that the water at all times flows freely under it. It should also extend for a short distance above the level of the water. In order that it may remain at all times at substantially the same height above the water and at a uniform distance below the top of the water, I attach the board to floats 38, one at each end and one in the middle, and in order that the floats may be maintained in proper position I surround them with a guard formed in part by the side walls 30 and in part by walls 39, which together with the side walls 30 form float chambers for the floats 38. There is a narrow throat 40 to each chamber so as to allow the water to freely enter the chamber, but the throat is so narrow that the float cannot slip out.

As already stated, Figure 4 shows the simplest form of construction having only a single water wheel which has a spread equal to the entire width of the sluiceway. In Figure 9 there is shown a construction for a double row of wheels in the same sluiceway. The sluiceway is broken away

so that only one wheel of each row is shown. In this case the sluiceway will be made just wide enough to accomodate two wheels side by side. Both wheels are adapted to 5 revolve from right over to left, and this will be the case whichever direction the current flows. In the direction viewed in the drawing in Figure 9, the blades on the lower side of the upper wheel are moving toward 10 the right and the blades on the upper side of the lower wheel are moving toward the left, and the wheels are so constructed that at the point where the two blades come the nearest together they will just graze each 15 other. At this point the blades of the upper wheel are folded and those on the lower wheel are the most widely spread. The folded blades of the upper wheel serve to deflect the current against the blades of the lower 20 wheel, thus serving the function of a deflecting wall. There will be provided, however, the deflecting walls 31, 31^a and 32, 32^a connected with the side walls 30, 30 for the same purpose as previously described in 25 connection with Figure 4. There is required only one pair of fingers 18, 18' for the two wheels instead of two fingers for each wheel.

As already stated and as is well known, 30 there is a short time at the top of the flood and at the bottom of the ebb when there is no current at all, and for some period of time before and after the top of the flood, and just before and after the bottom of the ebb 35 there is very little current under normal conditions.

One object of my invention is to provide means to compensate for this stagnation, and I accomplish this by storing up water 40 in a reservoir at the flood of the tide which may be utilized to create an artificial current at the time when needed. One simple form of this is shown in Figure 1. In this figure there is shown a sluiceway C 45 bordered by the two vertical walls 30, 30 in which are shown a series of turbine wheels A. Alongside of this sluiceway I construct a reservoir D of which one side may be one of the vertical walls 30 of the 50 sluiceway and having walls 41 on the opposite side and at the ends. This reservoir has communication, as indicated at 42, with the sluiceway, and this is controlled by a gate 43. When the water is near the 55 height of the flood the gateway will be opened so that the water will rush into the reservoir, and this will produce an increase in the rate of flow of the current in the sluiceway to compensate for the normal 60 sluggishness at that stage of the tide.

The gate will be left open until the water flowing into the sluiceway has sufficient current to perform the required work without the assistance of the reservoir, and then 65 the gate should be closed. The gate should

be kept closed until at or about the time when the tide is at the lowest, and then the current being practically dead the gate 70 43 should be opened so as to let the water from the reservoir rush into the sluiceway and produce a current to continue the driving of the wheels. The gates should be closed with the return of the tide after the water has gained sufficient current or head 75 to perform the work required, and remain closed until at or about the top of the tide when the gates should be opened to again fill the reservoir as before.

In the modification shown in Figure 2 80 there are provided two reservoirs D', D'', one on each side of the sluiceway. By this means the sluiceway may be flooded from both sides.

In this form of construction the end walls 45 of the two reservoirs are formed with 85 walls which converge toward each other outwardly and are inclined to the side walls of the sluiceway. This is for the purpose of producing a deflection of the water.

In the modification shown in Figure 3, 90 there is shown a single reservoir D^a of somewhat oval form, and a sluiceway C', which at each end of the reservoir divides into two branches C²-C² which pass around on 95 opposite sides of the reservoir and unite again at the opposite end. There is a gate 43^a at one end of the reservoir, and a second gate 44 across the sluiceway at some distance away from the reservoir after the two branches are reunited so as to prevent 100 the water from flowing out while the reservoir is being filled.

What I claim is:

1. In combination with a sluiceway, a plurality of turbine wheels arranged in a row 105 transversely of the sluiceway, each of said wheels having blades with hubs which have the greatest diameter at the middle of the axial length of the hub, and which have a diminished spread from the middle toward each end, whereby the clearance space between the several wheels in each row is greatest at the top and at the bottom of the wheel and diminishes toward the middle. 110

2. A turbine wheel having blades with hubs which have the greatest diameter at the middle of the axial length of the hub and which have a diminished spread from the middle toward each end. 115

3. In combination with a sluiceway so located in a body of water that there is a constant flow of water therethrough, a plurality of turbine wheels each mounted on a vertical shaft in said sluiceway and arranged in series lengthwise of the sluiceway, a reservoir extending alongside of the sluiceway surrounded by an enclosure, one side of the enclosure comprising a wall which separates the reservoir from the sluiceway and having a gateway from the 120 125 130

reservoir into the sluiceway, a gate whereby the said way may be opened and closed at will so as to admit water from the sluiceway into the reservoir and to release water from the reservoir into the sluiceway, and a plurality of turbine wheels arranged in a row transversely of the sluiceway at each end thereof to regulate the rate of flow of the water from the sluiceway, each of the turbine wheels in said series having blades with hubs which have the greatest diameter at the middle of the axial length of the hub and which have a diminished spread from the middle toward each end, whereby the clearance space between the several wheels in each row is greatest at the top and the bottom of the wheel and diminishes toward the middle.

4. In combination with a sluiceway located in a body of water having a current which flows through the sluiceway and which has a varying level at different periods, a turbine wheel mounted on a rotary, vertical driving shaft in said sluiceway, and a plurality of current regulating turbine wheels arranged in a row transversely of the sluiceway between said first turbine wheel and each end of the sluiceway, said current controlling wheels each having blades with hubs which have a diminishing spread from the middle toward the top and toward the bottom, so that the clearance space between the several wheels in each row is greatest at the top and at the bottom of the wheel and diminishes toward the middle, whereby when the level of the water is at the line where the said hubs have the greatest spread there will be offered the greatest resistance to the flow of the water and the resistance will be di-

minished as the level of the water rises above or falls below said middle line.

5. In combination with a sluiceway located in a body of water having a current which flows through the sluiceway and which has a varying level at different periods, a turbine wheel mounted on a rotary vertical driving shaft in said sluiceway, and a plurality of current regulating turbine wheels arranged in a row transversely of the sluiceway between said first turbine wheel and one end of the sluiceway, said current controlling wheels each having blades with hubs which have a diminishing spread from the middle toward the top and toward the bottom, so that the clearance space between several hubs in each row is greatest at the top and at the bottom of the wheel and diminishes toward the middle, whereby when the level of the water is at the line where the said wheels have the greatest spread there will be offered the greatest resistance and the resistance will be diminished as the level of the water rises above or falls below said middle line.

6. In combination with a sluiceway located in a body of water so that there is a flow of water therethrough, a turbine wheel mounted on a rotary shaft in said sluiceway, an anchored floating stop at the entrance to the sluiceway extending transversely thereof so that the stop will rise and fall with the rise and fall of the water in the sluiceway, said stop extending for some distance above and some distance below the level of the water but having at all times an open passage for water below the stop.

In testimony whereof I affix my signature.
FRANK M. ZOTTOLI.
